INVENTOR

Charles S. Westland

UNITED STATES PATENT OFFICE.

CHARLES S. WESTLAND, OF PROVIDENCE, R. I., ASSIGNOR TO ADDISON H. WHITE AND HENRY L. FAIRBROTHER, OF SAME PLACE.

EXTENSIBLE DROP-LIGHT.

SPECIFICATION forming part of Letters Patent No. 255,224, dated March 21, 1882.

Application filed October 12, 1881. (No model.)

To all whom it may concern:

Be it known that I, CHARLES S. WESTLAND, of the city and county of Providence, and State of Rhode Island, have invented a new and useful Improvement in Extensible Drop-Lights; and I do hereby declare that the following specification, taken in connection with the accompanying drawings, forming a part of the same, is a full, clear, and exact description thereof.

My improvement is intended to enable a drop-light provided with a kerosene or other fluid burning lamp to be conveniently adjusted and held to any position from the ceiling 15 of the room within the limits proper for such domestic conveniences; and the invention consists generally in such a construction of the extensible supporting member of the lamp that the resistance of a confined cushion of air can 20 be made available for aiding in supporting the weight of the lamp and its attachments and the degree of such resistance be conveniently regulated to meet varying requirements.

Referring to the drawings, Figure 1 represents my improved drop-light in elevation and partly in section. Fig. 2 shows a section on line α α of Fig. 1. Fig. 3 represents in section a portion of the supporting-tube and the interior pipe.

30 A is a tube properly secured to and pendent from the ceiling of the room. B represents a kerosene-burning lamp, which in this instance is mounted in a harp-shaped frame or support, C. This frame, or at least one side of it, is tubular, and is connected by a suitable coupling, e, to the pipe D. This pipe is somewhat smaller in external diameter than the interior diameter of the pendent tube A, as indicated in dotted lines in Fig. 1, and shown in section 35 in Fig. 3. The drawing Fig. 1 represents the drop-light as standing near its highest elevation. The pipe D should be of sufficient length and extend enough into the tube A to permit the full amount of downward extension 40 required. The upper end of the pipe D is furnished with a piston, D', the sides of which should fit closely the interior bore of the tube A, so as to prevent the passage of air; and it will be found desirable in practice to pack the

50 piston with some suitable fibrous packing, as shown in Fig. 3. The lower end of the tube A is provided with a stuffing-box, A', Fig. 1, of well-known construction, so as to exclude the passage of air from within the tube A around the pipe D.

55 It is obvious that if the drop-light be lowered the air within the tube A below the piston will be compressed and the reactionary force caused by such compression, unless balanced by the weight of the lamp and its attachments, would cause the piston D' to be forced upward. In order, therefore, to regulate the air-resistance consequent upon the formation of an air-cushion between the lower face of the piston and the stuffing-box A', so that it will 60 be just equal to or but slightly in excess of the weight of the lamp, I perforate the pipe D with a sufficient number of holes, d, close adjoining the piston, as shown in Fig. 3, to enable the compressed air to enter through the same 65 and pass down the pipe into the frame C. To enable the excess of pressure to be relieved, I place at any convenient point—as, for instance, at the place usually occupied by the cock in a gas drop-light—a spring check-valve, E. This 70 valve is opened by means of a rod connected thereto, and furnished with a button-head, E', and is kept closed by the pressure of a spring, e, or it may be constructed in any other convenient way, so long as it will enable the excess 75 of air-pressure beyond what is required to sustain the lamp and its attachments at the desired height to escape until any tendency of the lamp to creep upward is relieved. When the lamp is to be raised toward the ceiling the 80 valve E should be again opened, so as to allow the external air to enter and supply the partial vacuum in the tube A, which otherwise would occur.

85 In order to prevent the air above the piston 90 from being compressed when the drop-light is elevated and from being attenuated when the light is lowered, a series of holes, a, are made at any convenient place in the tube A above the range of movement of the piston D', the air entering or discharging through which maintains always above the piston simple atmospheric pressure. The friction occasioned by 95

the packing around the piston D' and in the stuffing-box A' will aid in keeping the lamp suspended; but the amount of this friction is constantly diminishing in the use of the drop-light, and long before the piston and stuffing-box will leak air the packing will furnish but little resistance to the upward and downward movements of the drop-light.

What I claim as my invention, and desire to secure by Letters Patent as an improved drop-light for kerosene and other fluid burning lamps, is—

1. The combination, substantially as above set forth, of a pendent tube, a pipe arranged to slide within the bore of said tube, a piston attached to said sliding pipe, a stuffing-box preventing the escape of air from the mouth of the pendent tube, apertures in the sliding pipe connecting the annular space within the tube with the interior of the sliding pipe, and a relief-valve to permit the escape of any excess of air-pressure when the drop-light is low-

ered, and to permit the admission of air when the light is elevated.

2. The combination, substantially as above set forth, of a pendent tube, a sliding piston attached to a pipe arranged to move within the bore of the pendent tube, air-apertures to maintain an equilibrium of pressure located in the pendent tube above the range of movement of the piston, a stuffing-box to prevent the escape of compressed air at the mouth of the tube when the drop-light is extended downward, apertures in the sliding pipe connecting the annular space within the tube with the interior of the sliding pipe, and a relief-valve to permit the escape of any excess of air-pressure when the drop-light is lowered, and to permit the admission of air when the light is elevated.

CHARLES S. WESTLAND.
